UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION

SPRING CHAIR-SEAT.

1,215,790.

Specification of Letters Patent. Patented Feb. 13, 1917.

Application filed July 18, 1916. Serial No. 109,881.

To all whom it may concern:

Be it known that I, WILLIAM B. FOSTER, of Utica, in the county of Oneida and State of New York, have invented certain new and useful Improvements in Spring Chair- Seats; and I do hereby declare that the following is a full, clear, and exact description thereof, which will enable others skilled in the art to which it appertains to make and use the same, reference being had to the accompanying drawings, and to the reference-numerals marked thereon, which form part of this specification.

My present invention relates to spring chair seats meaning thereby seats that are provided with springs for rendering them more or less resilient.

The purpose of my present invention is to provide a spring chair seat of new, improved and economical but efficient and durable construction. Another object of my invention is to provide a spring chair seat which is simple as to the number and character of the parts used to make the seat and also as to the way in which the members are assembled.

A still further purpose is to provide an article of the class described wherein simple but efficient means are provided to allow the coiled springs connecting the two flat metallic strips to yield and return to original position without tending to wear or injure the cushion or other upholstering material supported upon the said strips and over the said springs.

Another purpose in this connection is to have said protecting means of such form and character that they will not interfere with the freedom of the spring or the resiliency of the spring seat and at the same time will be so formed as not to materially increase the cost of manufacturing the spring seat or the cost of assembling the article.

Other purposes and advantages will appear from the specification and claims herein set forth.

Figure 1 is a plan view of a spring chair seat embodying my invention, the inward ends of one pair of metallic strips being cut away to show the coil spring and arms thereof beneath.

Fig. 2 is a cross-sectional view on an enlarged scale on line 2-2 of Fig. 1.

Fig. 3 is a cross-sectional view similar to Fig. 2 of a modified form of my construction.

Fig. 4 is a cross-sectional view similar to Fig. 2 of another modified form of my construction.

Referring to the drawings in a more particular description it will be seen that I have shown my invention as applied to a simple chair seat frame ordinarily known as a dining chair although it is obvious that my construction is as applicable to other forms of chairs. My invention is equally applicable whether the chair seat frame to which it is applied be the main frame of a chair or one removably mounted in the main frame of the chair.

The chair seat frame shown is composed of a wooden front and rear piece 4 and 5 respectively between the ends of which and rigidly secured thereto are placed the side pieces 6 and 7. The side pieces are placed between the front and rear pieces in order to prevent strain upon the corner joints of the seat frame through the tension of the springs which are connected in the construction shown in Fig. 1 so that they tend to draw the front and rear pieces together. Strong strips 8 and 9 preferably metal and conveniently formed of hoop or band iron are arranged in pairs, with the necessary number upon the chair seat frame, with their outer ends firmly fastened as by nails 11 to opposite sides of the frame, that is to the front and rear pieces 4 and 5 respectively as the parts are assembled in the drawings, while the inner ends of said metal strips extend inwardly directly toward each other over or across the opening 10 of the chair seat frame. In the form of my construction shown in Figs. 1 and 2 metallic strips 8 and 9 are similarly constructed and equal in length and are of such a length as to over-lap one another for a considerable distance at the center of the chair as plainly indicated in the drawings.

Where the said strips over-lap each other they are entirely free of each other, but rest closely together with the flat lower side of the one to the flat upper side of the other so that there may be a relative sliding movement between said over-lapping ends as the said strips yield downwardly and then return, without separating the oppos-

ing and sliding faces of said strips and especially without separating the inner end of the upper strip from the upper surface of the lower strip. Part way out on the strips 8 and 9 are similarly shaped arms 12 and 13 respectively having their outer ends secured to the lower sides of said strips as by means of the rivets 14 while the said arms extend inwardly and downwardly and toward the central part of the opening 10 to be spanned by a given pair of strips 8 and 9.

The said arms 12 and 13 are so mounted upon their respective strips 8 and 9 as to have the inner ends of said arms held away from or below the over-hanging portion of said strips. As two strips 8 and 9 are assembled and mounted upon a chair seat frame the length and proportion of the parts are such that the inner ends of the arms 12 and 13 are spaced from one another a little more than the natural length of a coiled or helical spring 15. The helical spring 15 is interposed between the spaced ends of said arms and connected thereto preferably by having the last coil at each end of the helical spring bent at right angles to the plane in which it is originally formed thus making a hook 21 at each end of the spring which is readily hooked through an opening 16 near the inner end of each of said arms 12 or 13. A set of two metallic strips 8 and 9 with their arms 12 and 13 are assembled by hooking the helical spring 15 to the arms 12 and 13 as above suggested. When this set is to be placed upon a chair seat frame the outer end of one, as for instance 8, is laid flat upon the upper surface of the wooden front piece 4 and securely and permanently fastened thereto as by a short nail 11 being driven through a hole 17 near the outer end of said strip and into said wooden front piece of the chair seat frame. The outer end of the other strip is by similar means fastened to the rear piece 5 of the chair seat frame after the helical spring 15 has been placed under a slight tension by forcing the strip 9 to slide rearwardly a short distance relative to the strip 8.

After the necessary number of such sets have been secured to the chair seat frame it will be seen that there is provided a series of flat bands extending entirely across the chair seat frame from front to rear, each band consisting of the strip 8 and the strip 9 and that these strips are yieldingly held in a straight line as shown in Fig. 2 through the tension of coil spring 15 and the arms 12 and 13 connected to said strips 8 and 9. When a substantial weight is placed upon the chair the strain thereof forces the helical spring 15 to expand somewhat but only to a slight extent on account of the strength of the helical spring and the fact that only a slight downward movement upon the supporting means of the chair seat frame is de-

sired in this class of construction. As soon as the strain is removed the springs 15 again contract and draw the strips 8 and 9 back to a position in line with each other. It will be understood that the hoop or band iron or other metal of which the strips 8 and 9 are composed, is of such nature that the slight bend or curve forced thereinto by the downward yielding at their center of a pair of these strips will not be permanent but that the strips will return to their original shape as soon as the helical spring is relieved of the working strain it has received.

It will be noticed, furthermore, that the slight downward curve forced into each pair of strips 8 and 9 when they receive strain will cause their inward ends to slide slightly upon one another as the spring 15 yields. During this sliding movement and its reverse or sliding movement back to original position the inner extremity 18 of the over-lapping inner ends, in this case the inner end of the strip 8 will rest at all times flat upon the adjacent upper surface of the strip 9 and not be separated therefrom. It will be seen, therefore, that the upholstering or cushioning material resting upon the strips 8 and 9 will not be injured or worn and will not even be in contact with the expanding and contracting spring 15 which is disposed beneath the over-lapping strips 8 and 9. Also the arms 12 and 13 are far enough below the over-lapping portions of their strips 8 and 9 as to hold the coil spring 15 at all times out of contact with even the lower strip namely strip 9, thus preventing wear and especially preventing noise in the chair seat frame.

In Fig. 3 is shown a modification or modified form of my invention, in that the strip 9 has its inner end bent down and inwardly to form the arm 13^a to the inner end of which is connected one end of the spring 15 while the strip 8^a is extended so as to pass the said arm at 13^a of the strip 9^a and to overlap upon the upper portion of the strip 9^a. The strip 8^a has an arm 12^a similar to 12 of Figs. 1 and 2 to the inward end of which is connected the other end of spring 15. It will be seen that this construction will provide a flat band for the support of the upholstering material or cushion and that this band will yield downwardly under strain or weight and come back after the strain is removed in the way already described for the construction shown in Figs. 1 and 2 except that the sliding movement will take the place between the free end of arm 8^a and the intermediate part or the inner raised part of the strip 9^a.

In Fig. 4 is shown a further modification of my invention, in that the strips 8^b and 9^b have their inner portions bent down to form the spring-engaging arms 12^b and 13^b respectively similar in shape and purpose to 130

arms 12 and 13 already described, but integral with the strips 8^b and 9^b respectively. The inner ends of these arms 12^b and 13^b are provided with holes 16 through which are inserted the hooked ends 21 of the helical spring 15 in the same manner as hereinbefore described. The cushioning or upholstering material of the chair seat is kept from resting down against the helical spring 10 by means of strips 19 and 20 overlapping at their inner ends and operating in the same way as the inner ends of strips 8 and 9 do, but the outer ends of these strips 19 and 20 are fastened as by rivets 14 to the strips 8^b 15 and 9^b as plainly indicated in the drawings.

It will be seen that this construction will operate in the same way as other forms of my invention and will have similar advantages. The particular advantage of this 20 modified form is that the strain placed upon each set of strips and spring is placed upon two integral strips, one consisting of 8^b and 12^b and the other 9^b and 13^b instead of having the strain transmitted through the rivets 25 as in the form shown in Fig. 2. In the modification shown in Fig. 4 the rivets 14 simply have the work of keeping the strips 19 and 20 up from the coiled spring 15.

It will be seen that various modifications 30 and changes may be made in the form and details of my construction without departing from the spirit of my invention as herein set forth.

I claim—

1. In a spring chair seat, the combination 35 of a rigid chair-seat frame having an opening therein, flat metallic strips arranged in pairs with their outer ends secured to opposite sides of the frame and with their inner ends overlapping one another, an arm on each strip slanting downwardly and inwardly with their inward ends held spaced from the line of the said strips and with the inward ends of the arms of each pair of strips spaced from each other and a coiled spring connected at its opposite ends to the inner ends of said arms and tensioned to 40 yieldingly hold said strips in line.

2. In a spring chair seat, the combination 50 of a rigid chair-seat frame having an opening therein, flat metallic strips arranged in pairs with their outer ends secured to opposite sides of the frame and with their inner ends overlapping one another, an arm on each strip slanting downwardly and inwardly with their inward ends held spaced from their over-hanging strips and with the inward ends of the arms of each pair of strips spaced from each other and a coiled spring connected at its opposite ends to the inner ends of said arms and tensioned to 55 60 yieldingly hold said strips in line.

In witness whereof I have affixed my signature, this 13th day of July, 1916.

WILLIAM B. FOSTER.
